UNITED STATES PATENT OFFICE.

CLARA L. COOK, OF EL MONTE, CALIFORNIA, ASSIGNOR OF ONE-HALF TO EMMIE T. NOLEN, OF EL MONTE, CALIFORNIA.

CALENDAR.

Application filed May 8, 1922. Serial No. 559,277.

To all whom it may concern:

Be it known that I, CLARA L. COOK, a citizen of the United States, residing at El Monte, in the county of Los Angeles and 5 State of California, have invented a new and useful Calendar, of which the following is a specification.

This invention relates to a calendar which may be used for ascertaining the day of 10 the week for any predetermined date.

In carrying out this invention I provide a condensed calendar chart by which one can easily and quickly ascertain on what day of the week the first day of any month 15 occurs within a required period as 100 years more or less.

An object is to provide a mechanical device that can be easily adjusted to exhibit a full calendar for any month in any year 20 covered by the chart.

Other objects are cheapness, ease of construction and operation, and practicability for every day use.

An object of the invention is to provide 25 a simple method for ascertaining dates of days in any predetermined year.

In carrying out the invention I provide a frame having on its rear side a chart of the character stated, and having on its front 30 side a slide-way marked along its edges with the days of the week equally spaced apart and a slide provided with the numbers of the days of the month correspondingly spaced apart.

Other objects, advantages and features of 35 invention may appear from the accompanying drawings, the subjoined detail description and the appended claims.

The accompanying drawings illustrate the 40 invention.

Figure 1 is a rear view of the calendar showing a chart extending over a period of one and three-fourths centuries.

Fig. 2 is a section on line x^2 , Figs. 1 and 5.

Fig. 3 is a section on line x^3 — x^3 , Figs. 1 and 4.

Fig. 4 is a front view of the calendar, adjusted for the month of January in the years 1919, 1930, 1936, 1941, 1947, 1958, 50 1964, 1969, 1975 and other years.

Fig. 5 is a view analogous to Fig. 1 show-

ing the calendar adjusted for the month of February in leap years 1920, 1948 and 1976.

Fig. 6 is a view of one side of the slide used for designating the various months. 55

The frame or main body of the calendar is formed of front and rear rectangular pieces 1, 2, which may be of any suitable material, such as sheet-metal, card-board or the like, joined by any suitable means as 60 the clips 3; or such main body may be formed from a single piece folded upon itself, as shown at 4, in Fig. 3. The front piece 1 of the calendar has an aperture 5 of suitable size to disclose the name 6 of 65 a predetermined month. Said names 6 are printed on a month designating slide 7 which is adapted to slide from end to end between the front and back pieces 1, 2 of the calendar in such a manner that only the 70 name of the predetermined month will be presented to view. A thumb piece 8 is provided at the top line of said slide 7 to facilitate movement thereof and hooks 10, 11 are provided at the top 9 of the slide 7, and 75 rest on the pieces 1, 2, to support the month designating slide 7 in the body of the calendar, said slide is in the present instance reversible and contains on one side the names of the first six months of the year, 80 and on the other side the names of the remaining six months. It is understood that the same may be so constructed that all the names of the months will be on one side of the slide. Underneath the name of each 85

month there is applied a mark 12 showing the number of days in said month. The month of February appears twice to accommodate both the common and leap year, thereby necessitating seven names on one 90 side of the month indicating slide 7 or thirteen names altogether.

A day of the month indicating slide 13 is provided at its top and bottom respectively with the numerals a representing the 95 numbers of days of the month and this slide is adapted to slide in a slide-way 13' formed in the front piece 1 and said numerals a are visible through an aperture 14. A thumb-piece 15 provides convenient means for moving said slide 13. The top and bottom respectively of the aperture 14 are provided 100

with week day indicating marks 16, there being a sufficient number of such marks 16 to provide seven different combinations for each calendar month. The indicating marks 16 on the top of the aperture 14 do not indicate the same day of the week, respectively, as the indicating marks 16 along the bottom of the aperture and that are directly underneath the marks along the 10 top of the aperture, i. e., the indicia along the top of the aperture begins and ends with Sun. and the indicia along the bottom of the aperture begins and ends with Tue. An adjustable finger 17 is pivotally connected to the slide 13 and is adapted to cover any one of the last three numbers, viz. 15 29, 30 and 31, which designate the days of the month as shown in Fig. 5 or such finger may be adjusted as shown, in solid 20 lines Fig. 4, to disclose all of the numbers.

The rear piece 2 of the calendar is provided with the chart or table T by which may be determined the day of the week on which the first of each month from the 25 year 1818 to 1997 inclusive, respectively occurs.

The spaces *n* which are arranged at the longitudinal edges of the calendar, have therein indicia in the form of numerals 30 designating different years from 1818 to 1997 inclusive. The marks 18 which designate the days of the week are arranged in vertical columns with respect to the year numbers in the spaces *n* and in horizontal 35 columns with respect to the marks 19 which designate the various months.

To determine on what day of the week any past; present or future date will come one has simply to find the required year 40 number in one of the spaces *n* then follow up or down, as the case may be, its vertical column of marks 18 until opposite the mark 19 designating the month in which the required date is, and such mark 18 arranged 45 horizontally of the required month will designate the day of the week on which the first of such month will come. Then on the front of the calendar adjust the slide 7 so that the required month appears in the aperture 5 which is open to one side of the body 50 of the calendar and likewise move the slide 13 so that the number one of the numerals *a* will be directly beneath one of the marks 16 at the top of the aperture 14, corresponding 55 to the day mark 18 previously ascertained in the table T.

The day of the week corresponding to the remaining days of such month will be found either above or below the numerals 60 *a* representing the days of the month.

A star *s* placed at the head of a year number in the space *n* designates that the same is a leap year.

For example, in case one desires to find

the days of the week corresponding to the 65 days of the month of January 1919, the day of the week on which the first of January came, may be found by following the vertical column *c* in which the year 1919 is designated, up to the horizontal space *d* in 70 which the month of January is located and determine that the first of January came on Wednesday.

The slide 7 is moved so that the month of January is visible through the aperture 75 5 as shown in Fig. 4, and as there are 31 days in the month as indicated at 12 the finger will be so positioned as to uncover the numerals *a* as shown in Fig. 4. The slide 13 will then be so positioned as shown 80 in Fig. 4 that number one of the numerals *a* will be underneath Wed. of the marks 16. The succeeding week days will be found above or below the consecutive days of the month designated by the numerals *a*. 85

Should Feb. of 1920 be desired it will be seen by the star *s* that such was a leap year and by following the above method that the 1st of the month came on Sunday, and the slides 7 and 13 will be adjusted accordingly, as shown in Fig. 5.

I claim.

1. A device of the character described having a body provided with a plurality of orifices open to one side thereof; a slide 95 movable longitudinally in said body and having indicia thereon to represent the months of a year and being movable in said body to bring into register with one of said orifices indicia representing the various 100 months of the year; indicia disposed above and below said other orifice representing the days of the week; the days of the week indicated by the indicia disposed below the orifice being for different days, respectively, than the days directly above each day indicated by the lower indicia and disposed above the orifice and a slide having indicia thereon representing the days of the month and adapted to cooperate with the indicia 105 representing the days of the week.

2. A device of the character described having a body provided with an orifice open to one side thereof; indicia above and below said orifice representing the days of the week, the days of the week indicated by the indicia below the orifice being for different days, respectively, than the days indicated by the indicia directly above each day indicated by the lower indicia and disposed above the orifice; and a slide movable in said body and having indicia along its longitudinal edges representing the days of the month and adapted to cooperate with the indicia representing the days of the week for the purpose specified. 115

3. A device of the character described having a body provided with an orifice

open to one side thereof; indicia above and below said orifice representing the days of the week, the first and last indicia above said orifice designating Sunday, and the first and last indicia below said orifice designating Tuesday; a slide movable in said body and having indicia along its longitudinal edges representing the days of the month and adapted to cooperate with the

indicia representing the days of the week ¹⁰ for the purpose specified.

In testimony whereof, I have hereunto set my hand at Los Angeles, California, this 29th day of April, 1922.

CLARA L. COOK.

Witness:

JAMES R. TOWNSEND.
